Serial Copy of a copy of
Letters Patent.

The schedule to in these Letters Patent, and making part
of the same containing a description in the words of the said
Israel Aszall, himself of his improvement in the machine
for boring holes in Rock.

Be it known that I, Israel Aszall of Elbert, with County
West Tennessee, have made an improvement in the machine
for boring holes in rocks; which is described as follows.

This machine consists of the following principal parts. 1. The frame
2. The anger & dice. - 3 The spring. 4. The side & bottom supports.
1. The frame is constructed by fastening together two posts about
7 feet high, & about 4 $\frac{1}{2}$ inches thick, one on top. The sill kept about
7 feet wide, & of the same thickness as the posts, & the two posts & sill
in about one foot of the top, are made two mortises about one inch wide
4 $\frac{1}{2}$ feet long, to admit the side springs to be hereafter described.

2. The anger & dice. The dice is about 8 feet long, made of round enough
iron, having a square nut on the top, & a female screw to receive the anger
The anger or bit is about 3 feet long & made in the usual way, but the top of
the anger is a screw by which it is fastened to the dice, by means of a
square collar & the use of a wrench to screw it to the dice.

3. The spring. The top spring is made of wood about 10 feet
long & of sufficient strength for the purpose intended; This spring is
fastened to the top of the dice by the nut & screw before mentioned,
in the center of this spring are two iron plates, one above & the other below
to prevent it from warping. This spring may be of a spiral or any other
form. The side springs are also made of wood, placed under the ends
of the top spring, & are connected with four guides, two on each side of
the frame & worked up & down in the side mortises before mentioned
which are supported at four heights by four posts into the holes in
the

The side pieces are made of wood, and are held in place by two
wedges, similar to those used in a sawmill. The machine is supported by two
long side pieces, and the top of the machine is supported by two cross pieces, the middle
one is attached to the lower spring by a screw and is regulated by a screw
passing through the iron rod. The frame of the machine is made of wood and
is very strong and steady, intended to be a bottom support. There
are two top supports about 7 feet high of perforated iron
the lower points down with iron to lay hold of the ground. They are
suspended by rings or joints from the side pieces mentioned above. The
bottom supports are made of iron or wood, with points to lay hold
of the ground. A guide, having an opening in it, is let into the
dill, this which the auger passes through keeps it in proper
direction whilst boring. On the upper surface of the lower dill
is a vessel containing water which is conducted to the opening
thus the dill. Operation. The machine is placed over the rock
to be bored, & the auger driven into the first timber which the
hole is intended to be bored. The top & bottom supports are made
to bear solidly. The auger is brought through the guide in the dill, the
boring commenced; the top side springs, supporting most of the
weight of the dill & auger & bit. —

What I claim as my invention, & wish to have by
Patent, is the construction of the whole of the above described
machine; except the auger or bit. For a further illustration
of my invention, I refer to the Model & drawing of the same
deposited in the Patent Office.

In Testimony whereof, the foregoing is a true specification
of my invention, I have made oath to the same & subscriber
my name before two witnesses at the City of Washington
the 5th day of April 1858.
